AI

N° 247.

Altitude Instrument

AI Patented Aug 9, 1859.

Fig. 2.

Fig. 1.

Fig. 4.

Fig. 5.

Fig. 6.

Witnesses,

John G. Smith

Original Letters Patent No. 22,913.—Improved Instrument for taking Altitudes of objects in combination with the rotary bar E, the arrangement of the adjustable plate G, and of the lens Y and rotary cylinder H, and adjustable plate D, in connection with the dial M and plates G for holding the lens, and G having on its face a small square G to receive the image through the lens, in such relation to each other, and to the rotary bar E that it operates substantially as and for the purposes specified.

FREDERICK YEISER.

Inventor,
Frederick Yeiser14162
X 1449